UNITED STATES PATENT OFFICE.

DAVID STONE, OF NEW YORK, N. Y.

DESIGN FOR A BOOK-MARK.

SPECIFICATION forming part of Design No. 24,233, dated April 23, 1895.

Application filed February 7, 1895. Serial No. 537,665. Term of patent 7 years.

To all whom it may concern:

Be it known that I, DAVID STONE, of New York, in the county and State of New York, have invented and produced a new and original Design for a Book-Mark, of which the following is a specification.

Reference is to be had to the accompanying drawing, forming a part of this specification, in which the figure is a perspective view of a book mark embodying my design.

The leading features of my design consist in a series of diverging bands B, an ornamental center piece C from which the bands di-

verge, and the raised ornamentation A on the face of the bands.

A minor feature of my design is the pendants D, E, F, in the form of a heart, cross and anchor arranged on the faces of the said bands near their free ends.

I claim—

The design for a book mark as herein shown and described.

DAVID STONE.
